DESIGN FOR A HEATING STOVE

Ambrose D. Olds, Wichita, Kans., assignor to Coleman Lamp & Stove Company, Wichita,
Kans., a corporation

Application July 25, 1938, Serial No. 78,705

Term of patent 3½ years

To all whom it may concern:

Be it known that I, Ambrose D. Olds, a citizen of the United States, residing at Wichita, in the county of Sedgwick and State of Kansas, have invented a new, original, and ornamental Design for a Heating Stove, of which the following is a specification, reference being had to the accompanying drawing, forming part thereof.

The grille shown only on a part of the heater is extended throughout the front and side panels from the top to the bottom stippled portions.

I claim:

The ornamental design for a heating stove, as shown and described.

AMBROSE D. OLDS.
